UNITED STATES PATENT OFFICE.

WILLIAM LAIRD BROWN, OF LANSDOWNE, PENNSYLVANIA, ASSIGNOR TO WILLIAM E. HELME AND JOHN McILHENNY, TRADING AS FIRM OF HELME AND McILHENNY, OF PHILADELPHIA, PENNSYLVANIA.

PREPAYMENT GAS-METER.

1,233,307.

Specification of Letters Patent. Patented July 17, 1917.

Application filed May 10, 1915. Serial No. 26,957.

To all whom it may concern:

Be it known that I, WILLIAM LAIRD BROWN, a citizen of the United States, residing at Lansdowne, county of Delaware, 5 and State of Pennsylvania, have invented a new and useful Improvement in Prepayment Gas-Meters, of which the following is a full, clear, and exact description, reference being had to the accompanying drawings, which form a part of this specification.

My invention relates to prepayment gas meters in which the opening of a valve controlling the passage of gas is permitted upon the insertion of one or more coins and in 5 which the closing of the valve is effected by the operation of the meter mechanism, the relation of these two movements being such that the value of the gas delivered, at current rates, is equal to the value of the coin 0 or coins inserted.

The object of my invention is to provide new and improved means to actuate the valve in both closing and opening; to indicate the amount of unconsumed gas standing 5 at any time to the credit of the consumer; to effect the jamming of the coin controlled mechanism, without rupture of the driving connections from the meter mechanism, in such manner as, under ordinary conditions, 0 to close the valve tightly in the event of slight leakage around the valve when the latter is closed at the end of normal movement of the mechanism actuated by the meter; to prevent jamming of the movable 5 carriage relative to the coin controlled shaft when said carriage is moved to its extreme position at the end of its manually effected actuation; and to avoid strain on the index mechanism.

0 A preferred embodiment of the invention accomplishing the foregoing objects is shown in the accompanying drawings, in which—

Figure 1 is a plan view of a gas meter known commercially as the "Simplex prepayment meter", with the cover removed. Fig. 2 is a front elevation of the mechanism shown in Fig. 1. Fig. 3 is a partial front view of the meter. Fig. 4 is a section

0 on the line 4—4 of Fig. 1. Fig. 5 is a section on the line 5—5 of Fig. 1. Fig. 6 is an enlarged detail sectional view of the jamming means for the valve-opening shaft.

The gas meter has an inlet α through

which gas enters valve chamber b , from 55 which the gas passes to the meter through port c under control of valve d carried by arm e on rock shaft f , which turns in bearings in valve chamber b and in a standard g on table h .

Slidable and turnable in standard g is a reciprocating carriage j into which is axially threaded a manually operated valve opening shaft m . Carriage j has a peripheral groove k adjoining a head l . Head l is 60 adapted, when the carriage is moved to the starting end of its movement, to engage a cut-off arm i on rock shaft f and thereby swing valve d to its closed position, groove k permitting arm i to swing into position 70 to so rock the shaft f .

Shaft m extends through the wall of the meter into a chamber n , in which is a set of reduction gears connecting shaft m with a shaft which is adapted, when rendered 75 operative by a coin, to be turned by hand so as to impart several rotations to shaft m , and thereby move carriage j so as to cause its head l to recede from arm i , thereby causing the surface of the disk beyond 80 groove k to swing arm i into position to open valve d . The coin-controlled mechanism within chamber n is not shown, as it forms no part of my invention, and may be of any of the known constructions. Preferably I 85 employ the coin-controlled mechanism which is the subject of a separate application for patent, Serial No. 843,785.

A gas-driven valve-closing shaft o , axially aligned with valve-opening shaft m , is of 90 non-circular cross-section and slides within an axial orifice of similar cross-section in an end head j' on carriage j , whereby carriage j is slidable relatively to shaft m but turns therewith.

The head l of carriage j has a peripheral groove within which is held one end of an arm p which extends through a slot in the gallery q of the meter and carries a pointer r adapted to move, with carriage j , along a 100 scale s , thereby indicating on the outside of the meter the amount of gas to the consumer's credit at any time.

Preferably shaft m is of such length as to permit the coin-inserting and manual shaft-turning operation to be repeated a number of times consecutively so as to adjust the meter for permitting a consumption of gas

- corresponding to the total value of the coins deposited. In the event that the maximum number of coins for which the machine provides is deposited, it is desirable to prevent carriage *j* from binding against a head or collar *t* integral with shaft *m*. This is accomplished by means of a wire or pin *u* which projects from the wall of valve chamber *b* in front of collar *j* at an angle slightly oblique to the plane of the radii of shaft *m*, whereby carriage *j*, in the extreme position specified, will engage pin *u* and thereby avoid the frictional locking with collar *t* that might otherwise occur.
- 15 A horizontal axle *v* transmits the motion of the meter mechanism (which may be of any known type and need not therefore be described) to the index mechanism *v'* which exhibits a record of cubic feet of consumption that may be read from the outside of the meter. Axle *v* drives shaft *o* by a worm *w* and worm wheel *x*. One end of axle *v* turns in a bearing in a standard *y*. The other end, which drives the main shaft of 25 the index mechanism, bears against a bracket *z* whose opposite ends are fastened to the table *h* and to the gallery *g*. Member *z* sustains the end thrust of axle *v* in the valve closing movement, as hereinafter more 30 particularly described.

Although valve *d* is intended to, and normally does, cut off the flow of gas through the meter when forced down upon its seat, if, for any reason, the valve permits gas to 35 pass when thus seated, the continued action of the meter mechanism, inasmuch as it cannot effect any further movement of carriage *j* along shaft *m*, tends to turn shaft *m* and the coin controlled mechanism positively 40 connected therewith as if it were manually operated. It is important to prevent this, in order that gas may not be delivered for which payment has not been made. The threads of shaft *m* are therefore so inclined, 45 and said shaft turns in its valve closing movement in such a direction, as to produce an axially outward jamming action of the shaft by which the coin-controlled mechanism is frictionally locked and prevented 50 from turning. This jamming action is made stronger by the fact that the head *t* of shaft *m* bears against the end *t'* of the stuffing box through which it extends on a comparatively narrow rim on its outer circumference 55 (see Fig. 6) so that friction exerted on said rim may have as great a resisting moment as possible. The coin controlled mechanism being thus prevented from turning, and the valve being seated but still allowing gas to pass, further motion of the meter mechanism will produce an increased pressure between valve and seat, thus tending 60 to stop the leak.

If, however, the leak is of such a nature 65 that no pressure within the limit of strength

of the device will make the valve tight, the abnormal torque produced by the continued movement of the meter mechanism will necessarily break some part of the mechanism, which should preferably be the most easily replaceable member. In the present construction the valve closing shaft *o* is in driving connection with the worm wheel *x* by means of a wire *x'* which will be broken in the event of abnormal resistance of shaft *o* 75 to rotation.

As hereinbefore stated, axle *v* in driving worm wheel *x*, is thrust toward the bearing *z*. The connection of the main shaft of the index mechanism with axle *v* is such that 80 the axle turns the shaft but is capable of a slight axial sliding movement relative thereto, so that the end thrust of the axle is not transmitted to the index mechanism.

Having now fully described my invention, 85 what I claim and desire to protect by Letters Patent is:

1. In a prepayment gas meter, in combination, a manually turnable valve-opening shaft, a carriage threaded thereon, gas-driven mechanism including a shaft of non-circular cross-section axially aligned with said valve-opening shaft and engaging a co-operating opening in the carriage and thereby adapted to turn the carriage and feed it along said shaft, a valve controlling the passage of gas, a member connected with and adapted to operate the valve, and means on the carriage adapted to turn independently of said member but adapted in the axial movement of the carriage to engage and actuate the first member and thereby actuate the valve to effect both its opening and closing.

2. In a prepayment gas meter, in combination, a manually turnable valve-opening shaft, a carriage threaded thereon, gas driven mechanism adapted to turn the carriage and thereby feed it along said shaft, a gas-control valve, means operable from the carriage to close the valve, and an abutment, the thread on said shaft being of such pitch and turning in such direction that the axial thrust imparted by the carriage thereto after frictional engagement of the shaft with the abutment prevents said shaft from being turned by said carriage after the latter has reached its valve-closing position, whereby further turning of the carriage necessarily effects a tighter closure of the 12 valve.

3. In a prepayment gas meter, in combination, a manually turnable valve-opening shaft, a carriage threaded thereon, gas-driven mechanism adapted to turn the carriage and thereby feed it along said shaft, a gas-control valve, means operable from the carriage to close the valve, a head on said shaft, and an abutment, one of the two last named members having a rim project-

ing toward the other member and adapted to be frictionally engaged thereby in the event of turning of said shaft at the end of the valve-closing movement of the carriage.

5. In a prepayment gas meter, in combination, a manually turnable valve-opening shaft, a carriage threaded thereon, gas driven mechanism adapted to turn the carriage and thereby feed it along said shaft, a head on the shaft, and means interposed between said shaft and carriage adapted to prevent a binding engagement between them at the end of the manually operable turning movement of said shaft.

10. In a prepayment gas meter, in combination, a manually turnable valve-opening shaft, a carriage threaded thereon, gas driven mechanism adapted to turn the carriage and thereby feed it along said shaft, a head on said shaft, and a pin projecting in front of said head and adapted to be engaged by said carriage to limit the movement of the carriage in the manually operable turning movement of the shaft.

15. In a prepayment gas meter, in combination, a manually turnable valve-opening shaft, a carriage threaded thereon, gas-driven mechanism adapted to turn the carriage and thereby feed it along said shaft, a head on said shaft, and a pin projecting in front of said head in a direction slightly inclined to a plane at right angles to the axis of the shaft and adapted to be engaged by said carriage to limit the movement of the carriage in the manually operable turning movement of the shaft.

20. In a prepayment gas meter, in combination, a manually turnable valve-opening shaft, a carriage threaded thereon, a gas-driven valve-closing shaft connected to the carriage so as to turn the same and slide relatively thereto, a worm-wheel on the valve closing shaft, a gas-driven axle, a worm thereon driving said worm-wheel, index mechanism, including a shaft connected

to said axle so as to turn therewith while permitting a longitudinal movement of the axle, and a bearing independent of the index mechanism adapted to receive the end 50 thrust of the axle.

25. In a prepayment gas meter, in combination, a gas-driven valve-closing shaft, a worm-wheel on said shaft, a gas-driven axle, a worm thereon driving said worm-wheel, the supporting table, the gallery, index mechanism back of the gallery and including a shaft connected to said axle so as to turn therewith while permitting a longitudinal movement of the axle, and a bearing 55 for the axle extending between the table and gallery and adapted to receive the end thrust of the axle.

30. In a prepayment gas meter, in combination, a manually turnable valve-opening shaft, a carriage threaded thereon, a gas-driven valve-closing shaft connected to the carriage so as to turn the same and slide relatively thereto, a worm-wheel on the valve-closing shaft, a frangible connection 70 between said worm wheel and valve-closing shaft, a gas driven axle, and a worm thereon driving the worm wheel.

35. In a prepayment gas meter, in combination, a manually turnable valve-opening shaft, a carriage threaded thereon, a head at one end of the carriage having a non-circular hole, a gas driven valve-closing shaft of corresponding non-circular cross-section extending through the hole in said 80 end head and an abutment adapted to frictionally arrest a turning movement of the valve-opening shaft imparted by the gas driven shaft and carriage after the latter reaches its valve-closing position.

40. In testimony of which invention, I have hereunto set my hand, at Philadelphia, on this eighth day of May, 1915.
